UNITED STATES PATENT OFFICE.

MICHAEL F. HERB, OF NEW WESTMINSTER, BRITISH COLUMBIA, CANADA.

PAPER-MAKING MACHINE.

Application filed July 14, 1923. Serial No. 651,532.

To all whom it may concern:

Be it known that I, MICHAEL F. HERB, a citizen of the United States of America, and a resident of the city of New West-
5 minster, in the Province of British Colum-
bia, Canada, have invented certain new and
useful Improvements in Paper-Making Ma-
chines, of which the following is a specifica-
tion.

10 My invention relates to improvements in
paper making machines the objects of the
invention being to so construct the stock
conveyor table that the stock discharged
thereon will maintain the same speed as the
15 wire cloth from the head box to the couch
rolls whereby the defect known as cloudi-
ness in the paper is eliminated.

The invention consists essentially of a con-
veyor travelling over a plurality of rollers
20 which are arranged to define a substantially
level upper run, an intermediate run set to
a graduated curve and a lower run of a
regular decline, as will be more fully de-
scribed in the following specification.

25 The drawing is a longitudinal section of
my invention.

The numeral 1 indicates a head tank from
which the pulp stock is fed to the table and
which is provided with a slice 2 which is
30 adjustable vertically to provide an outlet
gap 3 of any desired vertical depth at the
front of the head tank.

The numeral 4 indicates an endless wire
cloth conveyor the upper run of which is
35 caused to travel away from the head tank
and passes around a bottom couch roll 5,
which is suitably driven from any desired
source, at the lower end of the run, return-
ing over and under a plurality of idler rolls
40 6 and around a breast roll 7, the breast roll
7 is set under the slice 2 that the stock from
the tank 1 discharges onto the upper run
of the wire cloth 4 through the gap 3. 8 is an upper couch roll co-acting with the roll
45 5 and bearing upon the wire cloth 4 at the
outer end of its run. The numeral 9 is an
idler roll supporting the cloth adjacent the
couch roll 8. 10 indicates a plurality of
50 freely rotatable rolls upon which the wire
cloth is adapted to travel from the head
tank towards the couch rolls. 11 indicates
a plurality of suction boxes disposed trans-
versely of the wire cloth 4 which are open
55 at the top and are suitably connected to a
pump or other device for extracting water
from the paper as it passes thereover upon

the wire cloth. That portion of the upper
run of the wire cloth lying between the slice
2 and the lowermost suction box forms the
table 12. The rolls 10 supporting the table
12 between the slice 2 and the point A are
60 disposed to form a substantially horizontal
bed, the rolls supporting the portion be-
tween the points A and B are disposed to
describe a parabolic curve, the greatest
65 radius of which is adjacent the horizontal
section, the rolls supporting the portion of
the table extending between B and the suc-
tion boxes are disposed to form a constant
70 downward slope.

The numeral 13 indicates a pair of flanged
pulleys suitably mounted adjacent the sides
of the table, 14 indicates a corresponding
pair of pulleys mounted on opposite sides
of the head box 1. 15 indicates a pair of
75 deckel straps or rubber belts each of which
pass around one of the pulleys 13 and 14
and which on their outward run lie in close
contact with the wire cloth 4 and form side
borders thereto to confine the stock to a
80 predetermined width. 16 are idler pulleys
adapted to support the slack of the return
run of the deckel straps 15.

The numeral 17 indicates the paper com-
ing from the cloth between the couch rolls
85 5 and 8.

Having thus described the several parts of
my invention I will now briefly describe its
operation.

The pulp stock is fed onto the head tank
1 and maintained at a predetermined level
with a view to providing a constant dis-
charge speed onto the table 12 through the
gap 3 and to the point A of the table, the
cloth 4 is adapted to run at a similar speed
90 to the discharge speed of the stock. During
the travel of the stock lengthwise of the
table the surplus water is allowed to pass
rapidly by gravity through the mesh of the
cloth 4 so that the consistency of the stock
95 is becoming proportionately less liquid, by
the time the stock passes the point A its
momentum would become less if it were not
for the increased decline of the table which
by being graduated to a predetermined
100 parabolic curve maintains the flow of the
stock at a speed equal to the travel of the
cloth, thus preventing the stock from either
overrunning or underrunning the cloth and
permitting the water to seep out through
105 the cloth thereby causing the minute fibres
of pulp to settle evenly upon the table. By
110

the time that the stock has reached the point B it has become semi-solid and the fibres are no longer subject to displacement the paper in its run after passing the point B to the 5 couch rolls is subjected to drying by suction over the suction boxes.

It will thus be seen that I have invented a paper making machine which automatically causes the paper stock to settle to an even 10 grain during its passage along the table resulting in a good grade of paper being produced with less difficulty than is usually encountered with machines now in common use.

15 What I claim as my invention is:

1. In a paper making machine, a conveyor, means for supporting the upper run of the conveyor to form a table onto which paper stock is discharged, such table comprising 20 a substantially horizontal upper portion, a sloping lower portion and an intermediate portion of appreciable length disposed at a graduated slope whereby the momentum

of the stock thereon is assisted by gravity to equal the speed of the conveyor. 25

2. In a paper making machine having a conveyor onto which paper stock is discharged longitudinally, a table comprising a substantially horizontal upper portion, a sloping lower portion and an intermediate 30 portion defining a parabolic curve.

3. In a paper making machine having a conveyor onto which paper stock is discharged longitudinally, a table comprising a substantially horizontal upper portion, a sloping lower portion and an intermediate 35 portion defining a parabolic curve the greatest radius of which is adjacent the upper portion of the table.

Dated at New Westminster, B. C., this 40
18th day of June, 1923.

MICHAEL F. HERB.
